UNITED STATES PATENT OFFICE.

HENRY ALBERT OLSSON, OF CINCINNATI, OHIO, ASSIGNOR TO THE BROMWELL BRUSH AND WIRE GOODS COMPANY, OF CINCINNATI, OHIO, A CORPORATION OF OHIO.

BRUSH-MACHINE.

1,184,987.

Specification of Letters Patent.

Patented May 30, 1916.

Application filed April 17, 1914. Serial No. 832,659.

To all whom it may concern:

Be it known that I, HENRY ALBERT OLSSON, a citizen of the United States, and a resident of Cincinnati, in the county of 5 Hamilton and State of Ohio, have invented certain new and useful Improvements in Brush-Machines, of which the following is a full, clear, and exact description.

This invention relates to brush machines 10 and more particularly to improved brush machines for drilling and filling brush backs or blocks simultaneously, such as shown and described in my co-pending application filed Mar. 19, 1913, Serial No. 755,340.

15 The principal object of the invention is to provide an improved brush machine of this character in which the back or block supporting members (sometimes referred to as supporting or clamping templets or platens) 20 may be automatically positioned so that the brush backs will be moved from hole to hole without the aid of specially cut cams.

Another object of this invention is to provide a brush machine of this character 25 which eliminates the difficulty experienced in the so called cam machines when dismantling them, which is necessary when changing from one set of cams to another, by providing improved mechanism whereby 30 the changing from one pattern or style of brush to another can be quickly and accurately effected by adjustment only.

A further object of the invention is to provide a machine which will be universally 35 adjustable so that a brush with tufts driven into the blocks on more or less slant, or no slant at all, can be made on one and the same machine without the replacement of parts or cutting of cams, but simply through 40 adjustment.

Still another object of my invention is to provide a brush machine in which the specially cut cams are eliminated, and in 45 which it is possible to add to or deduct from the number of holes desired in any brush pattern, increase or diminish the slant of the tufts or knots, and shift them from one location to another in the brush back, thus getting any desired arrangement or pattern 50 simply through adjustment of the various parts of the machine.

Another object of my invention is to provide a machine which will bore holes of a uniform depth in the brush backs or blocks,

when they are presented for boring and 55 filling at various angles, and no matter how great the desired angles, either sidewise or endwise, the holes are bored in the brush back to a uniform depth without the use of cams and adjustment of parts. 60

All of these objects I attain through the parts, combinations of parts, and details of construction which will be more fully described in the following specification, which shows a preferred construction of a machine 65 constructed in accordance with my invention.

In the accompanying drawings: Figure 1 is a side view of this improved machine. Figs. 2 and 3 are front and plan views respectively thereof. Fig. 4 is a cross section taken substantially on the line 4—4 of Fig. 3. Fig. 5 is a horizontal section taken approximately on the line 5—5 of Fig. 4. Fig. 6 is a section taken approximately on the 75 line 6—6 of Fig. 1. Fig. 7 is a plan view of the brush back supporting member employed in my invention. Fig. 8 is a sectional view through one of the brush back supporting members as shown in Fig. 7. 80 Fig. 9 is a fragmentary side view of the machine illustrating the mechanism for coupling the brush back supporting members of the machine together. Fig. 10 is a plan view of part of the mechanism thereof. Fig. 85 11 shows a diagrammatic view of the base of the brush back supporting members showing same in dotted line position. Fig. 12 is a similar view showing the same movement applied to the rocking carrying arms on 90 said supporting member. Figs. 13, 14, 15, 16 and 17 are details showing some of the different parts of said supporting members. Fig. 18 is a detail view showing how the push bars are clamped in position on the 95 pattern drum. Fig. 19 shows a modification of push bars and engaging sliding members.

Similar reference characters indicate corresponding parts in the different figures of the drawings.

In the present machine two work supporting members A and B are provided, each a duplicate of the other. Each of these members comprises a T shaped base 20 having a slot 51 in the head portion 53 thereof and slots 49 and 50 in the tail portion 52 thereof, transverse of each other, and mounted on the tail portion 52 is a bifur-

- cated standard 23. The side standards 24 secured to the base have projecting arms or brackets 25 extending laterally therefrom and carrying rollers 27 which are mounted 5 on the ends of each bracket 25 and engage the vertical slots or recesses 39 in the guide brackets 26. The vertical standard 23 is provided with spline-ways 28 in which the splines 29 on the movable block 30 travel.
- 10 The side standards 24 have wings 31 and 32 extending outwardly therefrom, said wings having slots 33 and 34 therein. These slots register laterally with slots 35 and 36 in wings 37 and 38 of the movable block 30.
- 15 Between the side standards 24 and the bifurcated standard 23, rocker arms 40 are mounted, which are provided with elongated slots 41 and flanges 42 at the fore ends thereof for securing the platen or 20 brush back holder 43 thereto. The arms 40 may be pivoted at any point along the slots 41 by means of the studs 44 carrying rollers 45 which engage the slots 41 in said arms. The studs 44 are mounted at a point along 25 the slots 33 and 34 in the side standards 24. (See Figs. 1 and 7.) The arms 40 carrying the brush back holders 43 are rocked by means of a connection with the sliding block 30, which is movable vertically in said 30 standard 23. A stud 47 passes through the arms 40 and through one of the slots in wings 37 or 38 in the sliding block 30, and is illustrated in this case as passing through the slot 35. The stud 47 carries rollers at 35 the ends thereof which engage the arms 40. Now when the sliding block 30 is operated up and down in the bifurcated standard 23, the arms 40 are swung in the arc of a circle (that is when the machine is coupled and 40 adjusted as shown for angle work) as shown diagrammatically in Fig. 12. The guide brackets 26 being fast on the arms 40 and having grooves or pathways 39 in which the stationary rollers 27 travel, it is seen that 45 although the arms 40 move in an arc of a circle, the distance between the boring tool 48 and the platen or brush holding back is always the same, the arms 40 being allowed to slide and rock on the rollers 45 carried 50 by the studs, to accomplish this feature.
- The guide brackets 26 have their slots or pathways 39 vertically disposed and the brackets are operated in a vertical plane. It will be noted that the stationary rollers 55 27 have their common center line or axis in vertical alinement or in the same plane with the center line of the slot 51 in the head portion of the base, see Figs. 7 and 8, and that the brush back E (shown only in 60 Fig. 8) always has that particular part of its surface which is next to be bored in alinement or coinciding with the axis of the stationary rollers 27. This part of the surface of the brush back therefore is also in 65 alinement with the center of the slot 51 of

the head portion of the base. By means of this positioning, construction and arrangement of parts, the point to be bored or filled on the surface of the brush back is always coincident, as it were, or in alinement with 70 the axis of the positioning rollers 27, thereby insuring a uniform depth of bore no matter what position the brush back may be in at the time of boring. This operation and arrangement of parts guarantees a boring of holes of uniform depth while the brush back is being bored for a brush with the tufts slanting at the sides, in other words, while the brush back is being swung in an arc of a circle vertically with relation 75 to the top of the table or frame of the machine.

The same principle is involved and employed in swinging the brush back endwise in an arc of a circle, or in other words, in a 80 plane parallel with the top of the frame or table on which it is mounted. To accomplish this I provide the slots 49, 50 and 51 in the base 20 of the brush supporting members A and B. The slots 49 and 50 are in the 85 tail portion 52 of the base 20 while the slot 51 is in the head portion 53. The slots 49 and 50 are preferably undercut as shown, and are engaged by the roller 54 mounted on a stud in one of the slots 55 and 56 in the 90 top 57 of the table or frame. This roller forms the pivot upon which the base 20 swings. A stationary shaft 58 passes up through the slot 51 in the head 53 of the 95 base and carries a roller 54' which rides in the slot or undercut portion thereof.

The base 20 is provided with a gear rack 59 which is engaged by and meshes with a pinion 60 tight on the shaft 58, and forms the means for swinging the base 20 in an 100 arc of a circle. The sliding block 30 (Figs. 8 and 15) which operates the brush back holder in an arc of a circle in a vertical plane, is mounted on and carried by a shaft 61 which passes through the base 20 and of 105 course is carried laterally therewith, a slot 62 (Figs. 7 and 8) being provided in the table top 57 to accommodate this movement. The boring tool 48 reciprocates in the line of its length, said line extended passing 110 over the center of the shaft 58 (Fig. 11). These movements of the sliding block 30 and the base 20 are accomplished by the actuating means comprising a pair of positioning forks 63 capable of lateral movement (Figs. 1120 1, 3 and 4), which movement is accomplished by the to and fro movement of a master pattern drum D in a manner to be described hereinafter. These forks are placed one above the other and comprise the prongs or 125 plates 64 which have beveled undercut edges 65 forming inclined planes which are engaged by elements (to be described) on the drum, pushing them either to one side or the other according to the movement de- 130

sired for the brush back holding member. The upper fork is secured to a sliding bar or back 66 which carries a gear rack 67, said gear rack meshing with a pinion gear 68 mounted on a shaft 69. The pinion 68 is integral with a gear wheel 70 which meshes with a sliding gear rack 71, having teeth on both sides thereof, and supported by brackets 71'. The sliding gear rack 71 meshes with pinion gears 72 which are mounted on the shafts 58 described above which, as stated, also carry the pinions 60 which drive the bases 20 by engagement with the gear racks 59 thereon. Thus the movement of the upper fork operates the base 20 of the brush back holding members and provides for the lateral movement of the brush back holding member.

The lower fork is so arranged, that when moved laterally it will cause the vertical movement of the brush back or movement in a transverse direction from that of the base 20 of the holding member or support. The lower fork is provided with the prongs or plates 64' which are mounted on a straight bar 73 which is mounted on suitable brackets 74 and forms a support for the bar 66 of the upper fork and upon which said bar 66 slides. Bell crank levers 75 are attached at one end to the fork bar or back 73 and pivoted at 76 to brackets 77 mounted on the cross support or rib 78 of the frame of the machine (Fig. 2). The other ends of the bell crank levers 75 are attached to the ends of shafts 79 which shafts are mounted in suitable journals 80 (Fig. 3) and carry a frame 81 at their upper ends. The frames 81 (Figs. 1 and 6) are provided with tracks or guideways 82 in which a sliding member or sled 83 operates laterally of the machine. The sleds 83 carry the shafts 61 which have been described and upon which the movable blocks 30 of the brush back holding members are mounted. The sled is provided with the transverse slot 84 to allow for the proper movement of the shaft 61 therein when the brush holding members are being adjusted horizontally. Thus when the bell crank levers are rocked by the lateral movement of the bar 73, it is seen that the shafts 79 are operated accordingly, thereby raising and lowering the sleds 83 and the shafts 61.

All of the actuating means comprising the fork supporting mechanism just described is mounted on suitable brackets on the cross brace, or rib 78 of the frame of the machine.

Referring now more particularly to the master pattern drum D which is adapted to coöperate with the positioning forks, 85 represents the hollow shaft upon which the drum is mounted, the said shaft being mounted in suitable standards 86 mounted on the base 87 of the machine. This shaft

carries eccentrics 88 which engage the supporting spiders or rings 89.

The spiders or rings which carry the drum mechanism are provided with two walls 88' which are provided horizontally opposite each other. The eccentrics 88 just fit in between these walls and therefore when the eccentrics are rotated they impart a reciprocating movement to said spider rings and hence move the entire drum. It will be noted that there is no engaging wall on the spider rings for engagement with the eccentrics at the top or bottom. A push bar ring 90 is mounted on the outside of said clamping rings or spiders 89 and is slotted around its periphery to receive a series of pairs of push bars 91 which bars are clamped in position in said slots by means of clamping rings 92. The push bars it will be understood are capable of being adjusted longitudinally of their length in said slots. Mounted inside of the push bar ring a toothed ring or ratchet 93 is provided and securely mounted which is adapted to be engaged by a dog or pawl 94 mounted on the yoke 95 which yoke is pivoted on a pin 96 in the spiders or rings 89. The yoke straddles a roller or sleeve 97 on the hollow shaft 85 and when the entire drum is moved backward the inclined surface 98 (Fig. 4) strikes the roller and oscillates the yoke moving it upwardly and the pawl 94 engaging the teeth in the ratchet ring 93 being mounted on said yoke, rotates said ring and consequently the entire drum. As the drum starts its return movement the lower end 99 of the yoke strikes the roller or sleeve 97 and brings the yoke and pawl in position to engage another tooth, thus imparting a step by step rotary movement to said drum. Mounted on the spider or supporting rings 89 laterally extending brackets 86' are provided which carry rollers 100 at their outer ends. The rollers travel on tracks 101 provided on the standards 86. Thus the drum is reciprocated on said rollers.

It will be understood that each pair of push bars 91 are adapted to engage the pair of positioning forks as their turn comes and as they are rotated into proper position for engagement therewith, and as the drum is operated to and fro, and that each push bar is properly adjusted according to the pattern or layout plan of the brush back to be bored and filled.

In case it is desired to do straight work on the machine that is, have all tufts in the brush back placed straight and not at an angle, coupling mechanism (Figs. 9 and 10) is provided. First, however, the pivot 54 in the brush holding member must be removed, and another stud similar to that shown at 47 must be mounted in a corresponding position on the opposite side of the shaft 61 to

cause the arms 40 to move straight up and down instead of in an arc of a circle.

A gear wheel 102 is provided on the shaft 69 rotating therewith. A gear rack 103 is carried by a frame 104 which slides in guides 105 underneath the top 57 of the frame of the machine. A threaded stud 106 threads into a threaded hole 107 in the movable frame 104 and is also threaded through a portion of the main frame of the machine. This enables the frame 104 to be drawn to and fro for the purpose of engaging said gear rack 103 with the gear wheel 102 for shifting the tables laterally. The gear rack 103 connects with the shafts 61 as shown at 108 in Fig. 10. A hand wheel 109 is preferably provided on the stud 106 for operating same.

The hollow shaft 85 upon which the drum 20 is mounted is mounted on a main drive shaft 110 which passes therethrough and is driven by a pulley 111 driven by any suitable means. The shaft 110 has another pulley 112 mounted at its opposite end which is connected by 25 means of the belt 113 to pulley 114 which drives the shaft 115 upon which it is mounted. The shaft 115 has a bevel gear 116 mounted thereon which meshes with a bevel gear 117 mounted on the shaft 118 suitably 30 journaled in the frame. The shaft 118 has a bevel gear 119 mounted at its opposite end which meshes with a bevel gear 120 mounted on the hollow shaft thereby imparting reciprocating motion to the drum through the 35 medium of the eccentrics mounted on said hollow shaft.

It is believed that the operation of this improved automatic machine will be clearly understood from the foregoing description.

40 Another advantage derived from this machine is in the position lock obtained against the further movement of the brush back supporting members after they have been positioned for boring and filling.

45 While in the accompanying drawings I have shown two tables, one for boring and one for filling, it is obvious that a single table could be used where the boring or filling is accomplished in a separate machine. Neither do I wish to be confined to any specific style or shape of positioning bars, as it is obvious that bars with V or U shaped slots 121 could be substituted instead of bars with beveled ends, (Fig. 19) in which 50 case a V or U shaped tongue 122 would be substituted for the positioning forks now used in the most acceptable form of my invention. It will also be understood that the 55 number of push bars carried by the drum 60 may be increased or diminished to accommodate brushes with a greater or less number of holes.

Inasmuch as many modifications in the construction of my invention may be made 65 without departing from the spirit and scope

thereof, I do not wish to be confined to the exact details shown.

What I claim as new and desire to secure by Letters Patent is:

1. In a brush machine, the combination 70 with a work supporting member, of a rotating pattern drum capable of a to and fro movement, and mechanism operated thereby, whereby said member is moved in an arc and transverse to the plane of said arc in a 75 straight path.

2. In a brush machine, the combination 80 with a work supporting member, of a rotating pattern drum, a series of push bars, mounted thereon, mechanism engaged by said push bars whereby the movement of said pattern drum and push bars operate the work supporting member in an arc and transverse to the plane of said arc in a 85 straight path.

3. In a brush machine, the combination 90 with work supporting members, of a rotating pattern drum capable of a reciprocating movement, push bars mounted thereon, mechanism coöperating between said pattern drum and said work supporting members whereby said work supporting members are operated in arcs in horizontal and vertical planes.

4. In a brush machine, the combination 95 with work supporting members, of pattern mechanism, slideable members operated by said pattern mechanism, means whereby said slideable members operate said work supporting members in arcs and transverse 100 the plane of said arcs in straight paths.

5. In a brush machine, the combination 105 with work supporting members, a pattern drum, mechanism on said drum for varying the pattern of the work mounted thereon, slideable bars controlled by said mechanism on said drum, said slideable bars co-operating with the mechanism for operating said work supporting members and means whereby said pattern drum is operated to 110 engage said slide bars and impart movement thereto.

6. In a brush machine, the combination 115 with work supporting members, means for moving said members in arcs and straight paths in horizontal and vertical planes, said means comprising a pattern drum, push bars mounted thereon, sliding members engaged thereby, and mechanism engaging therewith adapted to transmit motion to the work supporting members.

7. In a brush machine, the combination 125 with work supporting members, of means for moving said members in straight paths in horizontal and vertical planes, said means comprising a reciprocating and rotating pattern drum, push bars mounted thereon, slideable members operating thereby and mechanism connecting said slideable members with said work supporting members.

8. In a brush machine, the combination with work supporting members, of means for moving said members in arcs in horizontal and vertical planes, and straight paths in horizontal and vertical planes, said means comprising a pattern drum rotatable upon reciprocating bearings, a series of push bars mounted thereon, said slidable members operated thereby, and mechanism whereby said slidable members are connected to the work supporting members and operate same.
9. In a brush machine, the combination with work supporting members, of means for moving said members in arcs in horizontal and vertical planes, said means comprising a pattern drum capable of a reciprocating movement, means for rotating said drum during a portion of its cycle of reciprocation, said pattern drum having push bars mounted thereon, said push bars being adjustable along the line of their length, slidable members engaged thereby, and mechanism whereby said slidable members operate said work supporting members.
10. In a brush machine, the combination with a work supporting member, means for moving said member in an arc and in straight paths, said means comprising a pattern drum capable of reciprocation, means coöperating therewith for effecting intermittent rotation of said pattern drum, push bars coöoperative with said drum, slidable members operated by engagement with said push bars, and mechanism between said slidable members and said work supporting member whereby movement of the slidable members is imparted to said work supporting member.
11. In a brush machine, the combination with work supporting members, of means for moving said members in arcs and straight paths, said means comprising a rotary pattern drum, push bars mounted thereon and capable of longitudinal adjustment, actuating means intermediate said drum and said work supporting members whereby the engagement of said push bars affects the movement of said work supporting members, and means whereby said pattern drum is rotated step by step to bring each push bar into contact with said intermediate actuating means.
12. In a brush machine, the combination with work supporting members, of a pattern drum capable of a rotating and reciprocating movement, intermediate mechanism between said pattern drum and said work supporting members whereby the movement of said drum operates said work supporting members in arcs and straight paths, push bars mounted on said drum and adjustable longitudinally on said drum, said push bars engaging the said actuating means when the said drum is reciprocated thereby effecting and controlling the arc shaped and straight pathed movements of said work supporting members.
13. In a brush machine, the combination of work supporting members, of a pattern drum, a series of push bars mounted thereon and adjustable longitudinally, intermediate actuating mechanism between said pattern drum and said work supporting members, said push bars having their ends beveled to engage said actuating mechanism and said pattern drum being capable of reciprocatory and rotary movement.
14. In a brush machine, the combination with work supporting members, of a pattern drum, push bars mounted thereon and adjustable longitudinally, said pattern drum capable of a reciprocating and rotating movement, said push bars mounted in radially disposed slots around the periphery of said pattern drum, intermediate mechanism between said pattern drum and said work supporting members, said mechanism actuated by engagement with the said push bars thereby controlling the movement of the said work supporting members.
15. In a brush machine, the combination with work supporting members, of a series of push bars capable of a reciprocating movement and of a step by step movement for bringing each push bar into operative position, intermediate mechanism between said push bars and said work supporting members, said mechanism controlled and operated by said push bars, said intermediate mechanism comprising sliding members engaged by said push bars for effecting the movement of said work supporting members.
16. In a brush machine, the combination with work supporting members, of a pattern drum capable of a rotating and reciprocating movement, push bars mounted thereon, intermediate mechanism coöperating between said pattern drum and said work supporting members, said actuating mechanism including sliding members, said sliding members having contact extensions thereon for engagement with said push bars, said push bars forming a lock against further movement of said sliding members when in engagement therewith.
17. In a brush machine, the combination with work supporting members, of a pattern drum, a series of push bars longitudinally adjustable thereon, intermediate mechanism between said pattern drum, and said work supporting members, said mechanism being controlled and operated by engagement with said push bars, said pattern drum capable of a reciprocating movement.
18. In a brush machine, the combination with work supporting members, of a pattern drum capable of a reciprocating movement, a series of push bars longitudinally adjust-

- able thereon, sliding forked members controlled by engagement with said push bars, intermediate mechanism between said sliding forked members and said work supporting members whereby the movements of said forked members control the movements of said work supporting members. 5
19. In a brush machine, the combination with work supporting members of a pattern drum capable of a reciprocating movement, push bars mounted thereon and adjustable longitudinally, sliding forked members in the path of said reciprocating drum and engaged by said push bars, intermediate mechanism between said forked members and said work supporting members whereby said work supporting members are moved in arcs and straight paths according to the movement and longitudinal adjustment of the 10 push bars on said pattern drum. 20
20. In a brush machine, the combination with work supporting members, of a series of groups of push bars capable of a reciprocating movement, said push bars adjustable longitudinally, a group of sliding forked members operated by engagement with said push bars, intermediate mechanism between said sliding forked members and work supporting members whereby the movement of the 15 said sliding forked members operate the work supporting members in arcs and straight paths a distance commensurate with the longitudinal adjustment of said push bars and the sliding movement of said 20 forked members. 25
21. In a brush machine, the combination with work supporting members, of a pattern drum capable of a to and fro movement, a series of push bars adjustable longitudinally 25 thereon, sliding forked members engaged by said push bars and locked against movement when said push bars have reached the limit of their engaging stroke, mechanism between said sliding forked members and said 30 work supporting members whereby the movement of said push bars and said sliding forked members operates said work supporting members in arcs and straight paths. 35
22. In a brush machine, the combination with work supporting members, of a rotating pattern drum, push bars adjustable longitudinally thereon, clamping rings around said drum for holding said push bars rigid with said drum, intermediate mechanism between said drum and said work supporting members, said push bars adapted to actuate said intermediate mechanism for moving said work supporting members in arcs and straight paths. 40
23. In a brush machine, the combination with work supporting members, of a rotating and reciprocating drum, a series of push bars adjustable longitudinally thereon, means whereby said push bars are held rigid with said drum, an internal toothed ring in 45 said drum, an oscillating yoke, an engaging pawl carried thereby for engagement with said toothed ring, said pawl rotating said ring during the cycle of reciprocation of said drum, and intermediate mechanism co-operating with said work supporting members and engaged by said push bars for moving said work supporting members in 50 arcs and straight pathed movements. 70
24. In a brush machine, the combination with work supporting members, of a pattern drum, push bars mounted thereon, a spider ring in said drum, a rotating eccentric operating in said spider ring for imparting a reciprocating movement to said drum, intermediate mechanism between said drum and said work supporting members, said mechanism being engaged and operated by said push bars when said drum is reciprocated, thereby imparting movement to said work supporting 75 members. 80
25. In a brush machine, the combination with work supporting members of a rotating and reciprocating drum, a slotted ring on said drum, push bars mounted in the slots of said ring, means for holding said push bars in rigid relation with said drum, mechanism intermediate said drum and said work supporting members whereby said work supporting members are operated in 85 straight paths and arcs during the reciprocating movement of said drum. 90
26. In a brush machine, the combination with work supporting members, each member having straight pathways therein transverse of each other, and guiding means engaging said pathways of means for actuating said members in arc shaped and straight pathed movements. 100
27. In a brush machine, the combination with work supporting members, each comprising transversely slotted members mounted one upon the other and adapted to move in transverse planes, engaging means for said slots, and means for accomplishing the movement of said slotted members in planes transverse of each other. 105
28. In a brush machine, the combination with work supporting members, each comprising members having straight slots at right angles to each other, and one member mounted upon the other and movable thereon in a plane transverse to the plane of movement of the other, engaging means for said slots, a pattern drum, and intermediate 115 co-operating mechanism between said drum and said work supporting members for imparting movement thereto. 120
29. In a brush machine, the combination with work supporting members, each comprising members having straight slots at right angles to each other, and one member mounted upon the other and movable thereon in a plane transverse to the path of movement of the other, engaging means for said 125 130

slots, a pattern drum, and intermediate mechanism between said drum and said work supporting members for imparting movement thereto.

- 5 30. In a brush machine, the combination with work supporting members, each comprising members having transverse slots therein and one member mounted on the other, of means for actuating one of said slotted members in arcs of a circle in one plane and in straight paths in a transverse plane, and means for actuating the other member in arcs of a circle in one plane and straight paths in a transverse plane, the movements 10 of each straight slotted member being respectively in transverse planes to the movement of the other straight slotted member.
31. In a brush machine, the combination with work supporting members, each work 20 supporting member comprising movable members mounted one upon the other and having transverse guideways therein, means for actuating one of said movable members in arcs of a circle and in straight paths, 25 means for actuating the other movable member in arcs of a circle and straight paths in a transverse plane to the plane of movement of the other, means for accomplishing said movements, said means comprising a pattern 30 drum, reciprocating push bars and intermediate mechanism between said pattern drum and said work supporting members engaged by said push bars and adapted to impart movement to said work supporting members.
32. In a brush machine, the combination 35 of work supporting members, each comprising movable members having transverse guideways therein, one member mounted on the other, means for actuating one of said 40 movable members in an arc of a circle in a vertical plane and in a straight transverse horizontal path, means for actuating the other member in arcs of a circle in a horizontal plane and transversely in a straight 45 path in a vertical plane.
33. In a brush machine, the combination with work supporting members, each comprising movable members having transverse 50 guideways therein, one member mounted on the other, means for actuating one of said members in an arc of a circle and straight paths in a vertical plane, means for actuating the other member in arcs of a circle and straight paths in a horizontal plane, the said 55 means including sliding actuators, a series of push bars, said push bars mounted on a rotating pattern drum capable of a to and fro movement, an intermediate mechanism between said sliding actuators and said work supporting members.
34. In a brush machine, the combination 60 with work supporting members, each comprising a base having straight, transverse guideways therein, means for actuating said base in arcs of a circle, pivots for said base,

70 said base being adjustable on said pivots and a member mounted on said base and movable in a transverse plane thereof, with means for operating same.

35. In a brush machine, the combination 75 with work supporting members, each comprising a base having straight transverse guideways therein of means for actuating said base in arcs of a circle, pivoting studs upon which said base swings, said studs adjustable in said guideways, said means for actuating said base comprising a pattern drum, a series of push bars mounted thereon, sliding actuators engaged by said push bars, intermediate mechanism between said sliding actuators and said work supporting members, and said pattern drum capable of a rotating and a to and fro movement.

36. In a brush machine, the combination 80 with work supporting members, each comprising movable members having straight, transverse guideways therein, of means for actuating one movable member in arcs of a circle in one plane, means for actuating the other movable member in straight paths in a transverse plane.

37. In a brush machine, the combination 85 with work supporting members, each comprising movable members having transverse guideways therein, of means for actuating one movable member in an arc in one plane, means for actuating the other movable member in a transverse plane and in straight paths, said movements accomplished by means of a pattern drum, a series of push 90 bars mounted thereon, said drum being rotatable and reciprocable, sliding actuators engaged by said push bars and intermediate mechanism between said sliding actuators and said work supporting members, studs 95 supported by said mechanism adapted to engage the transverse guideways in said supporting members whereby said members are guided in their respective movements.

38. In a brush machine, the combination 100 of work supporting members, each adapted to carry a brush back to be worked upon, and each comprising a horizontal movable member having a head and tail piece at right angles to each other and having straight 105 slots therein, a vertically movable member similarly shaped mounted thereon, stationary guiding means engaging the slots of each member, the axis of the guiding means for the head portions of each member being 110 substantially coincident at all times with that portion of the surface of the brush back which is in position for boring or filling, with means for accomplishing movement of 115 said movable members of the work supporting members.

39. In a brush machine, the combination 120 with work supporting members, of means for actuating said members in arcs of a circle in transverse planes, said means comprising 125

8
ing sliding forks slidable one upon the other and movable independently, intermediate mechanism between said sliding forks and said work supporting members, a rotary pattern drum, push bars mounted thereon and adapted to engage said sliding forks, said drum capable of a to and fro movement.

40. In a brush machine, the combination with work supporting members, of means for moving said members in straight paths, 10 said means comprising a rotatable pattern drum capable of a to and fro movement, actuating means coöperating between said drum and said work supporting members, 15 whereby the said work supporting members are moved in the same straight path.

41. In a brush machine, the combination with work supporting members, of means

for moving said members in straight paths, 20 said means comprising a rotatable, reciprocating pattern drum, actuating means between said drum and said work supporting members, a slidable frame, a gear rack thereon, gear wheels coöperating with said actuating means, said frame adapted to be 25 moved into engagement with said gear wheels and said actuating means for operating said work supporting members simultaneously in the same straight path, whereby 30 said work supporting members are operated in the same straight path.

HENRY ALBERT OLSSON.
